5 Claims. (Cl. 219—3)

1

This invention comprises improvements in or relating to electrical forging machines. It has always been difficult, in electrically heating workpieces which are held between electrodes, to ensure that the electric current enters the workpieces symmetrically, that is to say equally from opposite sides and especially is this the case when large workpieces are operated upon. One reason for this is that under the low voltages employed and with the very large currents necessary, small differences of resistance in the current leads or at the contacts or elsewhere have a marked effect; another reason is that the use of alternating current is a necessity and with large alternating currents under low voltages any difference in length of path of the current to different sides of the workpiece results in a difference in the inductive impedance to the current flow and therefore to a corresponding difference in the current distribution. Inasmuch as the transformer which supplies the current must be located to one side of the work, these differences are difficult to obviate. Especially at work-holding vices, which are also used as electrodes, there is difficulty in ensuring that both vice-jaws supply equal amounts of current to the work.

The present invention comprises, in an electrical forging machine the combination of a vice-electrode having two work-gripping vice-jaws, with a transformer having a secondary winding, one end of which is cut symmetrically by the plane of division between the two vice-jaws and flexibly connected to each of the vice-jaws, the connection to each vice-jaw being taken from the portion of the end of the winding which lies on the same side of said plane as the jaw to which it is connected.

In one construction according to this invention the vice-electrode may be constituted by jaws of high-conductivity metal held in a vice-frame of low-conductivity metal. Hitherto, ordinarily, vice-frames have been made part of the electrode, being made of high-conductivity metal directly secured to transformer terminals, but the use of distinct vice-jaws which constitute the electrode, so that the vice-frame is not directly connected to the transformer secondary, tends to confine the current to the jaws and workpieces and to limit irregularities of distribution arising from the necessarily irregular shape of the vice-frame.

When the invention is to be applied in upsetting the ends of workpieces or in heating the ends of billets an anvil-electrode may be provided in line with the vice-electrode, the other end of the

2

secondary of the transformer being disposed in the same plane as the first, close to the anvil-electrode, and flexibly connected thereto by connections symmetrical about the said plane.

If billets are to be heated at intermediate points between their ends two vice-electrodes each constructed as already described may be employed for gripping the workpieces at two places.

The following is a description, by way of example, of a construction of an electrical forging machine embodying vice-electrodes according to the present invention.

In the accompanying drawings:

Figure 1 is a front elevation of a complete upstanding machine embodying the present invention;

Figure 2 is a view of the vice of the machine showing some of the parts illustrated in Figure 1 as viewed from the right in that figure;

Figure 3 is a detail relating to the current connections to the vice;

Figure 4 is a further detail of the same;

Figure 5 is a detail of the current connections to the anvil.

Figure 6 is a diagram showing the disposition of the transformer.

The machine comprises a base plate 11 which is intended to rest on the foundations of the machine. On the platform at one end thereof is bolted a headstock, or guide-bar support, 12 which incorporates a cylinder block 13 containing a horizontal hydraulic ram 16 and securing means for two horizontal guide-bars 14, 15. At the other end of the bed-plate 11 is another headstock 17 incorporating a cylinder block 18 which contains a second hydraulic ram 19, axially in line with the first and securing means for the other ends of the horizontal guide-bars 14, 15. The two horizontal guide-bars 14, 15 are arranged so that one of them lies in a horizontal plane below the level and in front of the cylinder axis and the other is above the cylinder axis but to the rear thereof as can readily be seen in Figure 2. The two guide-bars therefore lie in an inclined plane which extends downwardly towards the front of the bed-plate of the machine; the axis of the ram cylinders 13, 18 is disposed in this inclined plane.

The guide-bars 14, 15 pass through the cylinder blocks 12 and 17 from end to end and are secured at the outer end by tension nuts 19, 20. Any compression forces exerted by the rams upon the workpieces held in the machine are wholly taken up by the guide-bars in tension and the reaction does not come upon the machine bed 11.

The hydraulic ram 19 of the cylinder block 17, which is at the left-hand end of the bed-plate 11 as viewed in Figure 1, is double-acting and has a long stroke; it is used for feeding the stem of the workpiece forward during the upsetting operation. The hydraulic ram 16 at the right-hand end of the bedplate is used to support an anvil 21. Upon the bedplate between the two rams and nearer to the ram 16 there is supported a vice-carrying casting 22. The vice-carrying casting has bosses through which the guide-bars pass and a web 23 connecting the bosses, which web is cut away at 24 in the centre between the upper and lower guide-bar to permit ready insertion of workpieces. A web 25 between and at right angles to the two guide-bars carries a bracket 26 which extends laterally from the web toward the anvil electrode and supports a fixed lower vice-jaw 27. The upper surface of this bracket 26 to which the vice-jaw is bolted is horizontal. Above the bracket and in front of the upper guide-bar 15 there is bolted to the web a vertical ram cylinder 28 carrying a hydraulic ram 29 which projects downwardly and carries a movable upper vice-jaw 30. It will therefore be seen that the vice-jaws are sub-divided horizontally and that the vice lies in effect at the bottom behind the lower guide-bar and at the top in front of the upper guide-bar. This arrangement makes for convenience in the insertion of the workpieces by the operator which is not otherwise easily achieved in a construction employing guide-bars. The two vice-jaws 27, 30 are made of high-conductivity copper alloy and have extensions 31, 32 which pass below the upper guide-bar 14 rearwardly towards a transformer located on the same level at the back of the machine, and shown in Figure 6. The upper and lower high-conductivity vice-jaws are made electrically identical with each other, that is to say they are of the same external dimensions and mass of metal and their connections to the secondary winding 76 of the transformer are made symmetrical so that the same current distribution will proceed to each vice-jaw, a result which has hitherto been difficult to secure. The body of the vice, that is to say the bracket 26, the web 23 and the hydraulic cylinder 28 are made of cast iron or steel.

The extensions 31, 32 terminate in enlarged terminal blocks 71, 72 and Figure 3 shows the rear face of the block 71. This face has six recesses machined out of it which are tapered. The tapered recesses are shown in the detail Figure 4 at 73, 74. In each recess is a thimble 75 and the thimbles 75 are soldered to the ends of heavy stranded copper cables 76. The cables 76 are bunched together and led around the core 61 of the transformer so that the cables themselves constitute the secondary winding of the transformer. The thimbles are held in place in the blocks 71, 72 by flat bars 77, 78, 79 which are placed so that they partly overlie the edges of the thimbles and extend close to the stranded cables 76. The bars 77, 78, 79 are held in place by set screws 80. The thimbles 75 are tapered so that they fit the tapered recesses 73, 74 in the backs of the portions 71, 72 of the extensions 31, 32 and thus good electrical connection is made to the vice-jaws. This connection is exactly symmetrical to the upper and lower vice-jaw and therefore the two jaws will get an equal amount of current. When, as in the generally adopted previous constructions, the transformer is located below the vice, with guide means for supporting the vice and anvils arranged horizontally on each

side of the vice, the connections to the upper vice-jaw have necessarily been longer than those to the lower vice-jaw so that the current distribution could not be symmetrical to the two jaws.

It will be observed that the vice-jaws 27, 30 contain liners 81, 82 and these liners may themselves contain bushings 83 which are of such a size as to fit the bar which is to be upset. The bushings 83 are made readily renewable. The liners are held in place by means of plates 85 and sliding dogs 86. On the side of the web 23 of the vice casting there are two bosses 33, 34 in which are secured the ends of control rods 35, 36 which extend parallel with the guide-bars 14, 15 to the headstock 17 of the ram 19, to which headstock they are also secured. The control rods 35, 36 lie in the same inclined plane as the guide-bars and between these bars; they are screwed for a length corresponding to the upsetting stroke and carry two stop nuts each, 37, 38. Mounted to slide upon the guide-bars and working between the stop nuts is a crosshead 39 to which is bolted the ram 19 of the hydraulic feed cylinder. The ram 19 is double-acting, with a large area behind it to exert forging pressure when it is moved toward the anvil and a small annular area between the piston rod of the ram and the walls of the cylinder 18 for purposes of retraction. On the crosshead, and coaxial with the ram, there is secured on the side toward the vice-jaw a thrust block 40 and in the thrust block there is screwed a work-engaging pad 41 having a recess to fit the end of the workpiece. A number of such pads of different sizes may be provided to fit different workpieces. The stroke of the ram in both directions is limited by the stop nuts 37, 38 on the control rods 35, 36. It may also be controlled by automatic limit switches or hydraulic pilot valves if desired.

Turning to consider the anvil-carrying ram 16 mounted at the right-hand end of the bed-plate, this ram is also double-acting and is secured to a crosshead 42 which slides upon the guide-bars 14 of the machine between the ram cylinder and the vice already described. To the crosshead there is bolted an anvil carrier 43, the anvil carrier being insulated from the crosshead by appropriate insulating packing 44 and by insulating bushings 45 in the holes which receive the securing bolts 45 or studs. It is this insulated anvil carrier and the anvil 21 clamped to its face alone which are made of high-conductivity material and the carrier 43 is provided with a rearward extension 46 which passes through the space below the upper guide-bar 14 and ends in a terminal block 47 arranged close to, and in the same vertical plane as, the terminal portions 71, 72 of the upper and lower vice-jaws already described. One end of the secondary winding 76 of the transformer is connected to this terminal block 47 and the other end symmetrically connected to the terminal portions 71, 72 of the upper and lower vice-jaws. The secondary winding of the transformer is therefore arranged in a horizontal plane as shown in Figure 6 and the magnetic circuit (the core 61) passes vertically through it. The primary winding of the transformer is indicated at 62. The other ends of the stranded cables 76 from those which are secured to the blocks 71, 72 are soldered into thimbles 75 similar to those already described and these are secured in tapered sockets in the terminal block 47 by means of bars 77 and set-screws 80 in a similar manner to that already described for the other ends of

the cables. This ensures an effective and satisfactory current distribution to the anvil 21. Although the current enters the side of the anvil carrier 43, it has to travel into the anvil 21 itself in an axial direction and will therefore be transmitted uniformly over the anvil face. Therefore by the described arrangement of the electrodes of the machine the anvil is symmetrically fed with current as well as the vice-jaws, and the work-pieces therefore readily become heated evenly throughout their cross-section.

The crosshead of the anvil-carrying ram has secured in it a pair of control rods 48, 49 which extend rearwardly towards the headstock 12 in which the ram is mounted so that these rods move with the crosshead. They pass through holes in the headstock and carry stop nuts 50, 51 in front of and behind the lugs, so that the stroke of the ram is limited in both directions and can be adjudged by the operator.

Control valves having hand levers 52, 53 are provided for the two hydraulic rams 16, 19 respectively and a valve having a lever 54 for the vice-electrodes. The control for the vice-electrodes may be linked in known manner with the control for the work-feeding ram 19 so that when the operator closes the vice-jaws on to the work hydraulic pressure is applied to the work-feeding ram to urge the workpiece towards the anvil. As soon as the workpiece reaches forging heat in the space between the vice and the anvil 21, the ram begins to feed it through the vice-jaws and to form an upset head against the anvil 21. The control 52 of the ram which carries the anvil is independent of the controls 53, 54 and is so regulated by the operator as to allow the anvil to recede slowly as the upsetting operation progresses so as to provide space for a head of the size desired.

Both the vice-jaws and the anvil can be provided with connections for water-cooling if desired and the vice-jaws may be provided with removable inserts held in place by special clamping means.

An electric motor 60 bolted to the bed-plate 11 drives a hydraulic pump within the bed-plate which supplies the hydraulic fluid under pressure required for operating the rams. The details of the hydraulic connections are common practice and do not require description.

If desired a steady rest 61 may be mounted on the guide-bars 14, 15 between the vice 22 and the crosshead 39 and may be provided with clamping devices for holding the centre of a long bar supported between the vice 22 and the thrust block 41 steady while it is being pressed forward by the ram 19.

I claim:

1. In an electrical forging machine the com-

bination of a frame comprising guides, a vice electrode supported on the guides comprising two work-gripping vice-jaws, one movable toward and from the other and means to operate said movable vice-jaw, the vice-jaws when closed being separated along a plane of division, a second electrode supported by the frame and insulated from the first electrode, said second electrode being located so as to be symmetrically cut by said plane of division, means to move one electrode along the guides relatively to the other, and a transformer comprising a secondary winding located so that it is symmetrically cut by said plane of division, one end being connected as to the part lying on one side of said plane to one vice-jaw and as to the part lying on the other side of said plane to the other vice-jaw and the other end of said winding being connected to the second electrode.

2. The combination according to claim 1 wherein the second electrode is an anvil-electrode in line with the vice-electrode.

3. The combination according to claim 1 wherein each vice-jaw has a lateral extension terminating in a terminal block having a fan which extends normally to the plane of division between the vice-jaws, the faces of the two terminal blocks being aligned on opposite sides of said plane, and means for attachment of one end of the transformer winding directly to said faces.

4. The combination according to claim 1 wherein the second electrode is provided with a lateral extension terminating in a terminal block having a face which extends normally to the plane of division between the vice-jaws and equally on either side thereof, and means are provided for attachment of one end of the transformer winding directly to said face.

5. The combination according to claim 1 in which the vice-electrode comprises jaws of high-conductivity metal held in a vice-frame of low-conductivity metal.
